UNITED STATES PATENT OFFICE.

FREDERICK DEACON MARSHALL, OF WESTMINSTER, LONDON, ENGLAND.

RETORT FOR THE TREATMENT OF CARBONACEOUS OR OTHER MATERIALS.

Application filed June 1, 1922. Serial No. 565,270.

To all whom it may concern:

Be it known that I, FREDERICK DEACON MARSHALL, a subject of the King of Great Britain, residing at 19 Queen Anne's Chambers, Westminster, in the county of London, England, have invented certain new and useful Improvements in or Relating to Retorts for the Treatment of Carbonaceous or Other Materials, of which the following is 10 a specification.

This invention relates to retorts for drying, roasting, calcining or distilling carbonaceous or other materials of the kind in which baffles or internal shelves are provided 15 for the purpose of lifting and showering the material under treatment so as to increase the surface exposed to the action of the hot gases passing through the retort.

According to one feature of the present 20 invention a suitable number of depending baffles or internal shelves are provided and arranged around the interior of an inclined rotating cylinder or retort, one end of each shelf being attached to the inner face of the 25 retort and the other end projecting inwards towards the interior, each shelf being inclined or curved relatively to a radius of the retort chamber and the arrangement around the periphery of the retort chamber of the 30 several shelves of each row being such that, in end view, they are disposed in a plane tangentially or approximately tangential to the circumference of the retort. Owing to the fact that the depending shelves or 35 baffles are arranged tangentially the material under treatment is lifted and showered in a more effective manner than heretofore and the efficiency of the retort is thereby enhanced owing to the increased surface exposed to the action of the hot gases, and the 40 longer time the material is allowed to remain in contact with the heating gases. The shelves or baffles may be of any suitable width and the surface of each shelf, which, 45 if desired, may be perforated or constructed as a grid, may be suitably bent into sinuous or corrugated formation so as to form pockets which facilitate the collection of the material from the bottom of the retort, and 50 also its elevation and deposition or showering upon the surface of the shelf immediately in advance of it at a point well beyond a vertical plane through the axis of the retort, thus carrying the material through 55 and beyond the upper part of the retort chamber where the major portion of the hot

gases travel. These pockets may be constituted by bending or curving each extremity of the shelf in the same direction, the part of the shelf between the curved ends being 60 curved in the reverse direction to that of the ends thereof. To stabilize the depending shelves the ends of each section may be connected together or covered with plates. These plates form stiffeners and at the same 65 time act as baffles which serve to force the heating gas to the sides of the retort where it is most needed. Each set of baffles may comprise four depending and tangentially 70 arranged shelves or plates of the character above described and they may be disposed in the same plane and at equal distances apart around the periphery of the retort, while any suitable number of such sets of shelves may be provided along the length of 75 the retort, each set being spaced apart from the next set of the series and the several sets of shelves being preferably staggered or angularly displaced relatively to each other. The shelves instead of being attached 80 in lines parallel to or in a direct line with the sides of the retort may be constructed to follow the curvature of the sides of the retort so that taken as a whole the shelves form portions of a spiral thus imparting a 85 twisting motion to the heating gases as well as showering the material in a more effective manner. Alternatively the shelves may be continuous, that it to say they may extend from end to end of the retort. 90

According to a further feature of the present invention means may be provided and disposed between each separate set of baffles or internal shelves or at the inlet end of the retort for the purpose of acting as a 95 further baffle for the heating gases so as to impart a whirling movement thereto as the hot gases pass through the retort from end to end thereof. Said means may be constituted by a propeller or the like of any 100 suitable shape or configuration which will serve to break up the direct stream of heating gases and impart a whirling motion thereto before the gases pass through the retort. An additional propeller or the like 105 may also be disposed at the entrance to the retort chamber so as to impart a whirling movement to the heating gases, which latter may be constituted by producer or water gas, before the gases pass through the first portion of the series. The propeller may, for 110 example, be of the type which is constituted

by a cone around which a number of spirally disposed vanes are secured, these vanes being themselves of cupped or curved formation, or by a plate from which the centre is 5 partially cut away so as to leave arms or wings which are bent outwards from the plane of the plate and twisted or bent in a similar manner to the blades of a propeller so as also to impart a whirling movement 10 to the heating gases. These propellers may be attached to the interior face of the retort by means of brackets, the arrangement being such as to leave sufficient space for the carbonaceous material under treatment to pass 15 freely between the propellers and the inner face of the inclined retort. By providing vanes or propellers as above described not only is a whirling movement imparted to the heating gases, thereby increasing their 20 efficiency in distributing heat to the material which is being showered or elevated by the shelves, but such vanes or propellers also serve to arrest and to deposit the dust which is travelling from end to end of the inclined 25 retort.

In order that the said invention may be clearly understood and readily carried into effect same will now be described more fully with reference to the accompanying drawing 30 which shows by way of example an inclined and rotary retort constructed according to the present invention and in which:—

Figure 1 is a longitudinal section of one constructional form of the improved retort, 35 and

Figure 2 is a section on the line 2—2 of Figure 1.

Figure 3 is a section through the line 3—3 showing the showering effect produced by 40 the baffles on the material under treatment during the rotation of the inclined retort, and

Figure 4 is a section through the line 4—4 of Figure 1.

Figure 5 is a section of a modified form of shelves in which the ends of the baffles are connected together, each cup or pocket of the element being completely enclosed so that the material does not leave the pocket 50 until it reaches the discharge end of the element, i. e., the material is gently turned over and over again in the same pocket and gradually makes its way towards the inlet end of the retort or the discharge side of the 55 element owing to the rotation and inclination of the retort. These pockets may be in the form of a spiral running the whole length of the retort or they may be divided up into spiral sections or elements as is the

60 case with the arrangement shown at Figures 1 to 4 so that the progress of the heating gases will be arrested in its course through the elements and thereby brought into more intimate contact with the material under 65 going treatment in the pockets.

Figure 6 is a longitudinal section of part of a modified form of retort constructed according to the present invention, the left hand end of the retort being a section on the line 6, 6 of Figure 7 and the right hand end 70 a section on the line 6—6 of Figure 8.

Figure 7 is a section through the line 7—7 of Figure 6 and

Figure 8 is a section through the line 8—8 of Figure 6.

A is the outer shell of the inclined retort. B, B are the supporting and driving bands for the retort said bands running on rollers B¹, B¹. C is a storage hopper for the carbonaceous material to be treated. D is a 80 device for feeding the carbonaceous material from the hopper C into the retort A, and which has a hollow interior D¹ which serves as an outlet for the gases evolved during the distillation of the carbonaceous materials within the retort A. E is the inlet for the gases for heating the material within the retort said gases being conveniently constituted by producer gas or water gas obtained from an adjacent producer (not shown). F is an opening in the retort through which the material is discharged. G, G (Figures 1 and 3) are the aforesaid depending baffles around the interior of the retort, one end g of each baffle 90 being attached to the inner face of the retort and the other end g¹ projecting inwards towards the interior. As shown, each shelf is corrugated or formed with pockets for the material under treatment 95 and is inclined relatively to a radius of the retort chamber. In the modified arrangement shown at Figures 6 and 7 the inner end g² of each baffle G¹ or internal shelf is 100 attached to a plate g³ which serves to stiffen the baffles and at the same time causes the hot gases to circulate around the periphery of the retort where it comes into contact in 105 a more advantageous manner with the material undergoing distillation. Alternatively 110 and as shown at Figure 5 the outer ends g may be embedded in the fireclay lining of the retort and their inner ends g² connected together in such a manner that the baffle or shelf G² forms a complete homogeneous 115 section provided with enclosed pockets within which the material is turned over and over in contact with the heating gases as it passes from end to end of the retort. 120 H and I (Figures 1, 2 and 4) and J (Figures 7 and 8) are alternative forms of devices which may be provided for the purpose of acting as further baffles and at the same time imparting a whirling movement to the hot gases which pass from end to end of the retort. In Figure 1 the baffle H is constituted by a plate from which the centre portion h has been cut away so as to leave 125 a number of arms or wings h¹, h¹ which are bent out and twisted at h², h² in a similar 130

- 5 manner to the blades of a propeller the plate H being attached to the periphery of the retort by angle irons h^4 , h^4 . A somewhat similar arrangement is shown at Figure 8 in connection with a retort which is lined with refractory material A¹ the ends j , j of the baffle being secured in place by being embedded within the refractory lining A¹. The baffle I is constituted by a propeller of the type which comprises a central conical portion i around which a number of spirally disposed vanes i^1 , i^1 are arranged, these vanes i^1 , i^1 being themselves of cupped formation and the propeller being secured in place on the retort by angle irons i^2 , i^2 . As shown in dotted lines at Figure 7 each set of baffles G¹, G¹ is preferably staggered relatively to the other so as to present a star-like appearance in end view. The material employed for the construction of the shelves, baffles or gas whirlers may be refractory fire clay, steel or iron, cast or wrought, according to the temperature employed in the retort.
- 25 6. A gas retort of the class described, comprising a rotatable cylinder having a series of longitudinally spaced baffles secured to the inner periphery thereof, and means in front of each of said series for imparting a whirling movement to the gas and deflecting it towards the periphery of the cylinder. 75
- 10 7. A gas retort of the class described, comprising a rotatable cylinder having a stepped series of longitudinally spaced baffles secured to the inner periphery thereof, and means in front of each of said series for imparting a whirling movement to the gas and deflecting it towards the periphery of the cylinder. 80
- 15 8. A gas retort of the class described, comprising a rotatable cylinder having a series of longitudinally spaced baffles, the baffles of each of said series being so positioned around the periphery of the cylinder so that in an end view each of said baffles is disposed in a plane substantially tangential to the circumference of the cylinder. 90
- 20 9. A retort for drying, roasting, calcining or distilling carbonaceous material and the like, comprising a rotatable cylinder having a longitudinal series of sinuous baffles secured to the inner periphery thereof, said series being stepped relative to one another, means disposed between the series of baffles which act to deflect the gas towards the periphery of the cylinder and impart a whirling movement to the gas as it passes through the said cylinder. 95
- 25 10. A retort for drying, roasting, calcining or distilling carbonaceous or other materials in which baffles are provided for imparting a whirling movement to the hot gases said baffles being constituted by a plate from which the centre has been partially cut away so as to leave arms or wings which are bent or twisted in a similar manner to the blades of a propeller. 100
- 30 11. A retort for drying, roasting, calcining or distilling carbonaceous or other materials in which a device is provided for imparting a whirling movement to the hot gases said device being constituted by a propeller of the type which comprises a cone around which a number of spirally disposed vanes are secured these vanes being preferably of cupped or curved formation. 115
- 35 12. A rotary and inclined internally heated retort for drying, roasting, calcining or distilling carbonaceous or other materials, comprising a cylinder containing a number of sections which are longitudinally spaced apart, each section being composed of a number of baffles, one extremity of each baffle being attached to the inner face of the retort 120
- 40 13. A gas retort of the class described, comprising a cylinder, a series of longitudinally spaced baffles secured to the interior of said cylinder, and means adjacent the inlet end of the cylinder, for imparting a whirling movement to the gas as it enters the cylinder. 125
- 45 14. A gas retort of the class described, comprising a rotatable cylinder, a series of longitudinally spaced baffles secured to the interior of said cylinder, and means in said cylinder for deflecting the gas toward the periphery of the cylinder. 130
- 50 15. A gas retort of the class described,

4
chamber and the other extremity being left free and projecting inwards towards the center of the retort, together with a plate located at the end of each section which connects together the free extremities of the several baffles of each section while leaving the center portions free so as to act both as a stiffener and as a baffle and cause the heating gases to enter each section at or towards the periphery of the retort.

13. A gas retort of the class described

comprising a rotatable cylinder having a number of longitudinally spaced sections each comprising a series of depending baffles, axially located cover plates positioned 15 at the ends of the baffles of each section, said cover plates acting as stiffeners and also as baffles which cause the heating gases to pass towards the periphery of the retort when entering the baffles of each section. 20

FREDERICK DEACON MARSHALL.
